Letters Patent May 12. 1834.

The Schedule referred to in these Letters Patent and making part of the same containing a description in the words of the said Noah Myott himself of his improvement in machinery for more thoroughly incorporating the substances used in the composition of bread —

To all persons to whom these presents shall come. — Noah Myott of Rington in the County of Plymouth and State of Massachusetts Bostonwards Breeding — Be it known that I the said Noah Myott have invented constructed made and applied to a certain improvement of machinery to be used for the purpose of more thoroughly incorporating the substances employed in making bread and expediting the process of rolling out the dough which invention I have herunto described and set forth in connection with the drawings attached which taken together form my specification — A represents a circular platform placed horizontally and turning on a vertical shaft. a passing through its center. said platform is furnished with small cleats affixed around its outer edge for the feet of a horse or other animal used for the purpose to rest against and give motion to the machinery. E is a cogged wheel on the shaft, as made of a proper size and material, the teeth of which engage with and rest on the teeth of a pinion & on the upright vertical shaft F. The shaft & turning at its upper bottom in proper boxes or supports is bent in the form of a bell crank in the center and has on the top or in any other convenient part of it a fly wheel B to regulate its motion — The crank part of the shaft has connected with it the end of a long pinion to manage more or less power when necessary. The said pinion is so made as backward and forward motion by the rotation of the crank and sets at its opposite extremity on the two toggle joints C. & D. which during a revolution of the crank are brought in a straight line motion. The upper end of the toggle C. is connected by a joint to the frame work C. while the

lower end of the opposite toggle δ is attached by a joint to the stamp D and the movements of the toggles δ and ϵ are alternately caused and reversed the upper stamp D . The stamp D vibrates in a proper bearing or quay α so that the lower end ϵ is run in the bearing. It is an upright bar of iron or cast iron material with an opening in the center to admit the passage through and longitudinal movements of the pitman. The said bar ϵ is connected at its foot by and turns upon a pin or bolt in a convenient part of the stamp D whilst it is attached and turns at its top by a similar pin or bolt to the end of the lever beam H turning on bearings or journals on the top of the frame work C at G . This lever beam H has its other extremity attached by a joint to the linked pull E shaped as seen in the figures or otherwise properly made — This pull E is moved upwards and downwards by the vibratory action of the lever beam H . On the top of the pull and connected to it by a joint is a governor rod K having a weight on its end. This weight can be inclined at an equal angle on each side of the perpendicular and as it is thrown either to the right or left its weight acts to bear one of the fenders against the double ribbed wheel L which it moves round during its rectilinear motions upwards and downwards. The double ribbed wheel L is composed of two wheels. The teeth of both a circumference are set in opposite directions, that is to say, those on the outer are acted on by the left fork of the pull, while those on the inner receive the right fork M which is least needed to play its turn. The wheel L is placed on the shaft N , which shaft N revolving in proper journals & boxes has on its other extremity a cog wheel O which plays into a cogged wheel attached to the underside of the moveable platform P sliding on friction rollers, and thus is properly suspended during its passage to and fro. — The dog Q being placed on this platform and this machine put in motion by animal or other force, the former is communicated from the cog wheel O to the former P in the shaft N from whence by means of the pitman δ to the toggles C of which are alternately brought into and out of line with each other and caused to depart from the stone thereby causing and suspending the stamp D the lower edge of

which is shaped like a blunt wedge to press the dough under as it is brought down upon it. By the intervention of the bar B. the lever beam E. and friction pullet acting together the motion of the stamper D. turns the ratchet wheel, its shaft M and pinion O moving the platform a proper distance to present to the lower edge of the stamper D. a fresh portion of the dough to be separated at every stroke of its downward - When the dough has been cut through once it is doubled up by the attendant who throws up the governor K. to the opposite side when the other part of the pull is brought to act in the ratchet wheel and reverse the movement of the platform P and brings the dough under the influence of the stamper D. and so on until it is sufficiently rolled for the purpose of baking.
 What I claim as my invention is the application of toggle joints to the stamper D. and the combination of machinery for moving the platform P. for accomplishing the above purpose of mine through by incorporating the articles used in the composition of bread.

In testimony that the above is a true specification of my said invention I have hereunto set my hand this nineteenth day of April in the year of our Lord eighteen hundred and thirty four.
